SAFETY RAZOR

Francesco A. Pica, Belleville, N. J.

Application July 19, 1935, Serial No. 32,289

1 Claim. (Cl. 30—41)

This invention relates to certain new and useful improvements in safety razors.

The primary object of this invention is to provide a safety razor of a compact nature having 5 the usual elements forming a safety razor and in addition having means for spraying a depth of water or other liquid upon the shaving area of a razor blade.

A further object of the invention is to provide 10 a razor of the above mentioned character provided with a hollow handle in which is mounted a piston for the purpose of forcing the liquid contained in the handle through diverging jets which are presented to the edge portion of the safety 15 razor blade, thereby assisting in cleaning the blade after usage.

A further object of this invention is to provide a comb member for a safety razor having elongated slots for the passage of the liquid whereby 20 such liquid may contact the edge areas of the safety razor blade in order to remove therefrom particles of hair and lather.

A further object of this invention is to provide 25 a safety razor having removably secured to the handle thereof a mirror which may be easily folded about the handle when not in use and which may be readily unfolded to provide an adequate reflecting surface when in use.

A still further object of this invention is to provide 30 a brush which may be also folded around the handle of the safety razor when not in use.

A further object of the invention is to provide an annular flared guard portion adjacent the diverging jets in the handle portion to prevent the 35 liquid from splashing rearwardly upon the user's clothes or hands.

Other objects and advantages of the invention will become apparent during the course of the following description forming part of the 40 specification and in which,

Figure 1 is a plan view of the safety razor embodying this invention;

Figure 2 is an enlarged vertical cross-sectional view of the same, taken on line 2—2 of Figure 1, 45 looking in the direction of the arrows, illustrating clearly the liquid dispensing arrangement and the arrangement of the jets for directing a spray of water upon the edge portion of the safety razor blade;

Figure 3 is a plan view of the safety razor comb illustrating the elongated slot therein for the 50 passage of the dispensed liquid;

Figure 4 is a transverse cross-sectional view 55 taken on line 4—4 of Figure 3, looking in the direction of the arrows illustrating the cross sec-

tional curvature of the razor blade comb and its general configuration;

Figure 5 is a transverse cross-sectional view taken on line 5—5 of Figure 2 looking in the direction of the arrows illustrating the diametrical- 5 ly opposite jets diverging from the hollow handle;

Figure 6 is a modified form of the invention illustrating the safety razor blade head removed and a sharpening device applied in lieu thereof;

Figure 7 is a side plan view of the razor blade 10 and sharpening attachment;

Figure 8 is a plan view of the foldable mirror illustrating the same in its extended position;

Figure 9 is a side plan view of the mirror illustrating the same folded around the handle portion 15 of the safety razor;

Figure 10 is a top plan view of the shaving brush illustrating the manner in which the same is being applied to the mirror before being folded around the handle of the safety razor; and 20

Figure 11 is a side elevational view illustrating the shaving brush in its folded condition, ready for use.

In the drawing, wherein for the purpose of illustrating the invention and wherein like reference characters will be employed to designate like parts throughout the same, the reference character 5 will generally be employed to designate a hollow safety razor handle having both ends open and the lower end is provided with a 30 plug 6 having a partial bore 7 terminating in diametrically opposite outwardly directed bores 8 which are surrounded by an outwardly flared guard 9. A boss 10 is formed integral with the plug 6 and is provided with internal screw 35 threads 11 for receiving the threaded stem 12 of a safety razor cap plate.

Mounted between the cap 13 and boss 10 is a safety razor guard or comb 14 which is provided with a central opening 15 for the passage of the 40 stem 12 and is also provided with opposite openings 16 for the passage of the usual stud carried by the cap plate 13. Formed between the openings 15 and 16 and the guard piece 17 are elongated slots 18 which are directly aligned with 45 the diverging bores 8 formed in the plug 6 so that liquid projected through the bores 8 may also pass through the elongated slots 18 and impinge upon the razor blade portion 19 which is sandwiched between the blade cap 13 and the 50 guard plate 14 in the usual manner.

The hollow handle 5 is provided with a reciprocating plunger 20 having an internally screw-threaded portion for receiving the screw threaded end portion 21 of an operating rod 22. The 55

opposite end of the operating rod 22 is also screw threaded as at 23 for receiving a handle or operating member 24 so that the plunger 20 may be reciprocated to force liquid toward the lower portion of the tubular handle 5 and through the diverging jets 8. When the cap member 24 is in its position shown in Figures 1 and 2, the same forms a closure for the open end of the tubular handle 5 to prevent the discharge of any liquid 10 contained therein when the handle is tilted upwardly.

In Figures 6 and 7, there is shown a modified form of the invention wherein the handle 5' is also provided with a boss 10' and an annular 15 guard member 9' for the diverging jets very similar to the form shown in Figure 2. By removing the safety razor blade structure including the parts 13, 14 and 19, a sharpening device may be secured to the handle including a frame 25 connected at the bottom by a cross bar 26 having a boss 27 provided with a screw threaded stud 28 for being threaded into the bore formed in the boss 10'.

Mounted between the frame member 25 is 25 journaled a blade holder 29 having clamping screws 30 at each end thereof for the purpose of gripping a razor blade 31 therein. One end of the pin (not shown) is provided with a gear wheel 32 which meshes with a gear wheel 33 intended to drive a roller 34 also mounted between the frame member 25 whereby the upper roller 35 and the lower roller 34 may contact with a flexible stropping member 36 to cause the swinging of the blade holder 29 thereby bringing the 35 blade edge 31 into contact with the stropping member upon reciprocation of the handle 5' in the usual manner.

In the modification shown in Figures 8 to 11 inclusive, a shaving mirror is provided including 40 a series of mirror strips 39 hinged together along the line 40. The mirror strips 39 may be formed from glass having a silver backing and in addition there may be provided a flexible cloth or the like in order to hold the sections securely hinged 45 together. The mirror may be folded around the handle 5 of the safety razor and held in position by an elastic band or other fastening means.

The shaving brush shown in Figures 10 and 11 may include a flexible strip of material 41 to

which may be secured bristles 42 so that the device when folded as shown in Figure 11, may form a shaving brush having sufficient qualities to perform the lathering operation prior to the shaving operation. In use, the device is wrapped as shown in Figure 11 and when not in use the device may be extended as shown in Figure 10 and wrapped around the handle 5 of the safety razor as shown in Figure 9 inside of the mirror 39. 5

When operating the liquid dispensing device 10 shown in Figures 1 to 5 inclusive, the handle 24 may be raised to withdraw the plunger 20 so that the hollow handle 5 may be filled with a liquid. The plunger 20 is then replaced and pressure exerted upon the handle 24 to cause the liquid to 15 pass out of the diverging openings 8 and when the safety razor blade cap 13 is partially unscrewed to release the tension on the blade 19, the liquid may pass through the openings 18 in the razor blade guard 14 and impinge upon the 20 edge portion of the razor blade portion 19 to remove foreign matter therefrom.

It is to be understood that the form of the invention herewith shown and described is to be taken as the preferred embodiment of the same 25 and that various changes in the shape, size and arrangement of parts may be resorted to without departing from the spirit of the invention or the scope of the subjoined claim.

I claim:—

A safety razor comprising a hollow handle, a piston reciprocably mounted in the handle, a plug fitted in one end of the handle having a central bore terminating in a plurality of outwardly directed ports, an annular flared guard 35 surrounding the outwardly directed ports, a boss carried by the plug, a cap plate having a stud adapted to be threaded into the boss, a guard plate having parallel elongated slots adjacent each edge thereof mounted on the stud between 40 the boss and cap plate and a razor blade mounted between the cap plate and guard plate the guard plate being spaced from the annular guard and discharge ends of the ports whereby water projected through the ports by action of said 45 piston passes through the guard plate slots for forceful contact with the adjacent portions of the razor blade for cleaning the same.
